UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

CONTROLLING DEVICE FOR POWER-OPERATING MECHANISM.

Application filed December 27, 1920. Serial No. 433,248.

To all whom it may concern:

Be it known that I, ARTHUR BATES, a subject of the King of Great Britain, residing at Leicester, in the county of Leicester, 5 England, have invented certain new and useful Improvements in Controlling Devices for Power-Operating Mechanism; and I do hereby declare the following to be a full, 10 clear, and exact description of the invention, such as will enable others skilled in the art to which it appertains to make and use the same.

This invention relates to controlling devices for power operating mechanism of boot 15 or shoe sole-moulding or other pressing or, it may be, cutting machines which it is desirable to provide with means safeguarding the operator from mutilation by parts moving under power to perform their action 20 on a workpiece presumed to have been placed between these parts.

As the class of machines known as Twin Sole Moulding Machine is typical of such machines and has customarily been equipped 25 with means as aforesaid, the invention will be hereinafter exemplified by reference to the application of a mechanism according to the invention to a machine of this class.

The objects of the invention are principally to provide means as aforesaid of a character safer than those in vogue or hitherto proposed and rendering the machine as a whole more convenient to operate.

A feature of the invention contemplates 30 the provision in a device of the class described for controlling the operation of a machine, having mechanism controllable to throw the machine into and out of operation and means acting automatically for controlling said mechanism to throw the machine out of operation, of means comprising two members operable by the respective hands of the operator, which is dependent upon the release and subsequent operation 35 of both of said members for controlling said mechanism to throw the machine into operation after being thrown out of operation by said automatic controlling means. It will be apparent that with such a construction 40 the release and subsequent operation of both of the hand operable members which is necessary before the machine can be thrown into operation after being stopped automatically, insures that the operator will employ both hands in starting the machine, as

it would be impossible for the operator to tie down one of the members so as to employ only one hand in starting the machine. In the preferred embodiment of the invention, the construction is such that the release 45 of either one of the hand operable members during the operation of the machine is resultant in the immediate stoppage of the machine, so that it is necessary for the operator to employ both hands to maintain the 50 machine in operation as well as to start the machine.

Other features of the invention which may or may not be employed in connection with the feature above referred to will be 55 hereinafter described and claimed, the advantages of which will be obvious to those skilled in the art from the following description and accompanying drawings.

Referring to the drawings,

Figure 1 is a side elevation showing in dot-and-dash lines the frame-work and parts of a twin sole moulding machine and in full lines the starting and stopping mechanism;

Figure 2 is a rear elevation showing the side frames of the machine in dot-and-dash lines and part of the starting and stopping mechanism in full lines;

Figure 3 is a detail view of the hand levers and associated parts by which the starting and stopping mechanism is controlled; and

Figure 4 is a plain view of the parts shown in Fig. 3.

The twin sole moulding machine illustrated in the drawings to which the invention is particularly applicable comprises two pairs of moulds arranged side by side between end frames, the lower mould of each pair of moulds being arranged to slide vertically towards and away from its stationary upper mould on vertical guide rods fixed in the framework of the machine. The lower moulds are arranged to move alternately towards and from their respective 90 stationary moulds and are actuated by toggle links connected to cranks set at 180° apart on a crank shaft having bearings in the end frames. The crank shaft is driven at a relatively slow speed by a driving shaft 100 also mounted in bearings in the end frames.

At the end of the driving shaft 1 is fixed a coned clutch member 2. A driving pulley 3 rotatably and slidably mounted on the shaft 1 has a hub 4 in which is formed a 110

peripheral groove 5 which receives trunnions 6 fixed in a lever 7 pivoted at 8 to the end frame 9 of the machine. The forked lower end of the lever 7 is pivotally connected to one end of a bar 10 the other end of which is pivotally connected to an arm 11 fixed on a shaft 12 rotatably mounted in bearings formed on the end frame 13 of the machine. The shaft 12 is rotated by a spring 14 fastened at one end to a second arm 15 fixed to the shaft 12 and at the other end to a hook 16 fixed in the frame 13 in a direction to move the bar 10 lengthwise (and incidentally, owing to the rotation of the arm 11, downwards) and through the lever 7 move the pulley 3 into engagement with the coned clutch member 2 to drive the machine. The bar 10 is held in its de-clutching position (as shown in Figures 1 and 2) by a roll 17 rotatably mounted on a pin 18 which is fixed in a head 19 formed on the lower end of a plunger 20. The plunger 20 is slidingly mounted in a block 21 fixed between two arms 22, 23. The arms 22, 23 are pivotally mounted on the driving shaft 1 and are connected near their upper ends by a distance piece 24 bolted between the arms. The plunger 20 is pivotally connected to an arm 25 of an eccentric strap 26 which surrounds an eccentric 27 fixed on the driving shaft 1 between the arms 22, 23 and by which the plunger is reciprocated in the block 21. The arms 22, 23 are swung about the shaft 1 either to move the roll 17 from under the bar 10 and allow the spring 14 to act to slide the pulley along the shaft 1 into engagement with the clutch member and drive the machine, or to move the roll 17 under the bar 10 so that as the plunger 20 is reciprocated it will raise the bar 10 and disengage the pulley and clutch member. The arm 23 is extended upwardly and at its upper end is engaged by a shoulder 28 formed on a pusher bar 29 which is pivotally connected by a pin 30 to one arm 31 of a bell-crank lever 32 pivoted at 32* to a fixed part of the machine. The other arm 33 of the bell-crank lever is pivotally connected by a pin 34 to the lower end of a rod 35 the upper end of which is connected by a pin 36 to one end of a connecting member 37 which is connected at its opposite end by a transverse pin 38 to the centre of an equalizing bar 39. The bar 39 is pivotally connected at each of its ends to the lower ends of links 40, 40, which are pivotally connected at their upper ends to hand-levers 41, 42 pivoted between their ends on the same stud 43 which is fixed in a casing 44, the right-hand link 40 being connected to the right-hand arm of the hand-lever 41, and the left-hand link 40 being connected to the left-hand arm of the hand lever 42. The casing 44 is fixed by a pin 45 to a fixed mould guide rod 46 of the machine. Latches 47

are pivoted on the hand-levers and are provided with notches 48 on their inner ends to normally engage stops on the casing and are held in engagement with the stops by springs one of which is shown at 49. To start the machine the operator must grasp both handles, to release the latches, and press downwardly on the hand levers. Through the links 40 and equalizing bar 39 a pull is exerted on the rod 35 thereby turning the bell-crank lever 32 on its pivot against the tension of a spring 132 and through the pusher bar 29 turning the arms 22, 23 about the shaft and withdrawing the roll from under the bar 10. The downward movement of one only of the hand-levers is not sufficient to effect the withdrawal of the roll from under the bar and the starting of the machine, it being necessary to depress fully both hand levers before the machine can be started and therefore both hands of the operator must be employed it being understood that the hand-levers are spaced well apart by the casing which encloses the hand-lever mechanism. Conversely if one only of the hand-levers is released the roll 17, just as soon as the plunger 20 brings it to its lower position, will move sufficiently under the bar so that the bar will be lifted and the machine stopped. The machine is automatically stopped, even if the hand-levers are still depressed, when one pair of moulds is fully separated and the other closed at the end of the cycle. For this purpose a cam 50 having two cam portions 51, 52 is fixed on the crank shaft 53 of the machine. Resting on this cam is one end of a bar 54 the other end of which is pivoted at 55 to the bracket which supports the bracket casing 44. A link 56 pivoted at 57 on the bar 54 is slotted at 58 near its lower end to receive the end of the pusher bar 29 which has a shoulder 59 formed near its end. A stop 60 adjustably mounted on the under side of the bar 54 limits the swinging movement of the link 56, under the influence of a spring 61, to position the link for engagement with the shoulder 59. As the pusher bar 29 is moved towards the rear of the machine to remove the roll 17 from under the bar 10 the link is swung away from its stop 60 by the shoulder 59 and when the bar 54 rides off the high part of the cam 51 the link 56 is lowered and its lower end snaps past the shoulder 59 and is positioned by the stop 60 with its slotted end embracing the deeper part of the bar 29 between the two shoulders 28 and 59. As the shaft 53 rotates the cam 52 raises the link which turns the pusher bar 29 on the pin 30 and disengages the shoulder 28 from the upper end of the arm 23 thereby allowing the roll 17 to be moved under the bar 10 by the spring 62 and during the next upward movement of

the plunger 20 the bar is raised and the machine stopped at the end of the cycle.

Before the machine can be re-started the pusher bar 29 must move towards the front of the machine a sufficient distance to allow the shoulder 28 to re-engage the upper end of the arm 23 and this forward movement requires the full release of both hand-levers. During the forward movement of the 10 bar 29 the shoulder 59 re-engages the lower end of the link 56.

The crank shaft 53 is driven from the driving shaft 1 at a considerably slower speed than the driving shaft, so that the 15 plunger 20 is reciprocated a number of times during a half revolution of the crank shaft (i. e. during the period between successive automatic stoppages of the machine) and therefore machine stoppage very quickly follows release of either hand-lever.

A projection 63 is provided on the head 21 the object of which is to secure that should the brake, which it is usual to provide in machines of this type, fail to act 25 and the shaft 1 continue to rotate by its own momentum the bar 10 will rest on the projection 63 as the plunger 20 is lowered and the pulley will thereby be held out of 30 engagement with the clutch member.

While it is preferred to employ the specific construction and arrangement of parts 35 illustrated and described, it is to be understood that this construction and arrangement is not essential except so far as specified in the claims, and may be changed or modified without departing from the broader features of the invention.

The nature and scope of the invention 40 having been indicated and a device embodying the several features of the invention in their preferred form having been specifically described, what is claimed is:—

1. A device of the class described for 45 controlling the operation of a machine having, in combination, mechanism controllable to throw the machine into and out of operation, means acting automatically for controlling said mechanism to throw the machine out of operation, two normally locked members operable by the respective hands of the operator, and means dependent upon the release and subsequent operation of both of said members for controlling said mechanism to throw the machine into operation after being thrown out of operation by said automatic controlling means.

2. A device of the class described for 50 controlling the operation of a machine having, in combination, mechanism controllable to throw the machine into and out of operation means for controlling said mechanism to throw the machine out of operation, and means acting independently thereof comprising two normally locked members oper-

able by the respective hands of the operator, dependent upon the release and subsequent operation of both of said members for controlling said mechanism to throw the machine into operation after being thrown out of operation by the first mentioned controlling means.

3. A device of the class described for controlling the operation of a machine having, in combination, mechanism controllable to throw the machine into and out of operation, means acting automatically for controlling said mechanism to throw the machine out of operation, two members operable by the respective hands of the operator, and means acting upon movement of both of said members to control said mechanism to throw the machine into operation and upon the release of either one of said members by one of the hands of the operator to control said mechanism immediately to throw the machine out of operation.

4. A device of the class described for controlling the operation of a machine having, in combination, mechanism controllable to throw the machine into and out of operation, means acting automatically for controlling said mechanism to throw the machine out of operation, two members operable by the respective hands of the operator, and means operated by the combined movements of both of said members either simultaneously or separately as desired to control said mechanism to throw the machine into operation and keep it in operation in that cycle only until one of said members has a contrary movement.

5. A device of the class described for controlling the operation of a machine having, in combination, mechanism controllable to throw the machine into and out of operation, two members operable by the respective hands of the operator, means dependent upon the combined operations of both of said members for controlling said mechanism to throw the machine into operation, and means acting automatically to control said mechanism to throw the machine out of operation and to disconnect said mechanism and said members, irrespective of continued operation of said members by the operator.

6. A device of the class described for controlling the operation of a machine having, in combination, mechanism controllable to throw the machine into and out of operation, two members operable by the respective hands of the operator, means dependent upon the operation of both of said members for controlling said mechanism to throw the machine into operation, and means acting independently of said members for controlling said mechanism to throw the machine out of operation.

7. A device of the class described for 130

controlling the operation of a machine having, in combination, mechanism controllable to throw the machine into and out of operation, two members operable by the respective hands of the operator, means dependent upon movement of both of said members to control said mechanism to throw the machine into operation and upon the release of either of said members by one of the hands of the operator to control said mechanism to throw the machine out of operation, and means acting automatically after a period of operation of the machine to control said mechanism to throw the machine out of operation.

8. A device of the class described for controlling the operation of a machine having, in combination, mechanism controllable to throw the machine into and out of operation, two members operable by the respective hands of the operator, and means acting upon movement of both of said members to a particular position to control said mechanism to throw the machine into operation and dependent upon both of said members being retained in such position by the employment of both hands of the operator to maintain the machine in operation.

9. A device of the class described for controlling the operation of a machine having, in combination, mechanism controllable to throw the machine into and out of operation, and means comprising devices requiring the use of both hands of the operator to control said mechanism to throw the machine into operation, and upon the release of one of said devices by the operator to control said mechanism immediately to throw the machine out of operation.

40 10. A device of the class described for controlling the operation of a machine having, in combination, mechanism controllable to throw the machine into and out of operation, two levers capable of being operated by the respective hands of the operator, means comprising two members associated with said levers respectively for locking said levers in position and requiring to be moved in one direction to release said levers, and means dependent upon movement of said levers in the opposite direction to said movement of said locking members to control said mechanism to throw the machine into operation.

45 11. A device of the class described for controlling the operation of a machine having, in combination, mechanism comprising a vibrating member movable in a direction transverse of the path of the vibration to throw the machine out of operation, two members operable by the respective hands of the operator, and means dependent upon the operation of one of said members for moving said vibrating member in the direction to throw the machine out of operation.

12. A device of the class described for controlling the operation of a machine having, in combination, mechanism controllable to throw the machine into and out of operation, means acting automatically for controlling said mechanism to throw the machine out of operation, two members operable by the respective hands of the operator, and means dependent upon the release and subsequent operation of both of said members for controlling said mechanism to throw the machine into operation after being thrown out of operation by said automatic controlling means, and upon the release of either one of said members to control said mechanism to throw the machine out of operation.

13. A device of the class described for controlling the operation of a machine having, in combination, a driving clutch member, a driven clutch member, mechanism for shifting the clutch members into and out of engagement, means for actuating said mechanism to shift the clutch members into engagement, power operated means for actuating said mechanism to shift the clutch members out of engagement comprising a reciprocating plunger, a carrier for the plunger movable in one direction to connect said plunger with said mechanism to actuate said mechanism to shift the clutch members out of engagement and movable in the opposite direction to disconnect said plunger and said mechanism, a spring for moving the carrier in the direction to connect said plunger with said mechanism, two members operable by the respective hands of the operator, means dependent upon movement of both of said members to move said carrier in the direction to disconnect said plunger and said mechanism, and upon the release of one of said members to permit said spring to move the carrier in the direction to connect said plunger with said mechanism, a cam, and means actuated by the cam to disconnect said hand operable members and said carrier to permit said spring to move the carrier in the direction to connect said plunger with said mechanism.

14. A device of the class described for controlling the operation of a machine having, in combination, mechanism for throwing the machine into and out of operation, means for actuating said mechanism to throw the machine into operation, power operated means for actuating said mechanism to throw the machine out of operation comprising a reciprocating plunger, a carrier for the plunger movable in one direction to connect said plunger with said mechanism to actuate said mechanism to throw the machine out of operation, and movable in the opposite direction to disconnect said plunger and said mechanism, a spring for

moving the carrier in the direction to connect said plunger with said mechanism, two members operable by the respective hands of the operator, means depending upon movement of both of said members to move said carrier in the direction to disconnect said plunger and said mechanism, and upon the release of one of said members to permit said spring to move the carrier in the direction to connect said plunger with said mechanism.

15 15. A device of the class described for controlling the operation of a machine having, in combination, mechanism for throwing the machine into and out of operation, a 20 spring for actuating said mechanism to throw the machine into operation, power operated means for actuating said mechanism to throw the machine out of operation comprising a reciprocating plunger, a carrier for the plunger movable in one direction to connect said plunger with said mechanism to actuate said mechanism to throw the machine out of operation, and movable in the opposite direction to

disconnect said plunger and said mechanism, a second spring for moving the carrier in the direction to connect said plunger with said mechanism, two members operable by the respective hands of the operator, and means dependent upon movement of both of said members to move said carrier in the direction to disconnect said plunger and said mechanism, and upon the release of one of said members to permit the second mentioned spring to move the carrier 40 in the direction to connect said plunger with said mechanism.

16. A device of the class described for controlling the operation of a machine having, in combination, a driving clutch member, a driven clutch member, mechanism for yieldingly engaging the clutch members and for positively disengaging the clutch members, two members operable by the respective hands of the operator, and means acting 45 upon movement of both of said members to control said mechanism to shift the clutch members into engagement, and upon the release of one of said members to control said mechanism to shift the clutch members out 50 of engagement.

ARTHUR BATES.
